(57) CLAIM

The ornamental design for an athletic garment, as shown and described.

DESCRIPTION

FIG. 1 illustrates a perspective view of the athletic garment showing the new design;

FIG. 2 illustrates a front view of one embodiment thereof;

FIG. 3 illustrates a back view thereof;

FIG. 4 illustrates a right-side view thereof;

FIG. 5 illustrates a left-side view thereof;

FIG. 6 illustrates a top view thereof;

FIG. 7 illustrates a bottom view thereof;

FIG. 8 illustrates a front view of another embodiment thereof; and,

FIG. 9 illustrates a left-side view of the embodiment shown in FIG. 8.

The broken lines shown in the drawings are included for the purpose of illustrating unclaimed portions and form no part of the claimed design.

The uniformly spaced broken lines on the surface of athletic garment, in FIGS. 1-9, represent stitching.
